UNITED STATES PATENT OFFICE.

WILLIAM GARRETT AND GEORGE GAYLETS, OF OLD FORGE, PENNSYLVANIA.

SEGMENT FASTENER.

Application filed November 30, 1921. Serial No. 519,023.

This invention relates to new and useful improvements in segments, and more particularly to means for fastening segments in place, the main object of the present invention being the provision of an improved segment and means for fastening the same in position to eliminate destruction of the same through the engagement of the contact fingers therewith.

10 The manner of fastening segments to the controlling drums of street car controllers and various other places, are somewhat objectionable in view of the fact that the ends of the segment are exposed in such a position that they will be readily engaged by the contact fingers when completing the circuit and the screws or other means which fasten the segments in place, have a tendency to wear upon the contact fingers, thus 15 destroying the usefulness of the same so that it is necessary to replace them with new fingers. It is therefore, one of the principal objects of this invention to provide means whereby this segment can be readily 20 attached to the controlling drum so that the ends of the segment are entirely out of the path of the contact fingers and the screws or other means which fasten the segment in 25 position are also removed from the path of 30 the contact fingers.

With the above and other objects in view, the invention consists in the novel features of construction, combination and arrangement of parts hereinafter more fully set 35 forth, pointed out in the claim and shown in the accompanying drawings, in which:

Figure 1 is a detail side elevation of a portion of a controlling cylinder showing the manner in which our improved segment 40 is attached thereto, and

Fig. 2 is a transverse sectional view taken on the line 2-2 of Fig. 1.

Referring now more particularly to the drawings, the numeral 1 indicates the main body of the controlling cylinder which is provided at intervals thereon with projections as at 2 having arcuate faces and provided with oblique end portions which extend inwardly from the arcuate face to the 45 body of the cylinder 1. It is to these arcuate faces that the usual copper segment is attached by having a single strip of copper, the length of the portion 2 attached thereto by inserting screws through the body of the

55 strip into the portion 2, thus leaving the heads of the screws exposed where they will engage with the contact fingers which ride over the segment for completing a circuit. The ends of the segment are also exposed to 60 engagement with the usual contact fingers whereby it oftentimes occurs that the contact fingers will engage the ends of the segment and bend them upwardly off of the arcuate face of the portion 2.

In order to eliminate engagement with 65 the contact finger of the ends of the segment and the screws or other fastening means which hold the same in position, it is our object to secure the segments in position upon the projections 2 in such a manner 70 that the ends of the segment and the fastening means will be entirely removed from the path of the contact fingers. To this end the segment 3 is shaped to conform to the arcuate contour of the face of the projection 2, a slight curve as at 4 being formed adjacent each end of the segment and the extreme end formed to fit tightly against the inclined end portions of the projections

2 as shown in Fig. 2, and perforated to receive a screw 5 which extends through the 75 perforated ends of the segment and is imbedded within the body portion of the projection 2. In forming the segment in this manner, it is apparent that in order to make 80 the ends of the segment fit tightly against the inclined faces of the projection, the curvature 4 is imparted within the segment instead of bending the ends directly at right angles, thus providing a smooth contact 85 face for the contact fingers which engage with the segment. As the contact fingers ride over the outer face of the segment 3, the fingers will not contact in any way with the fastening means for the segment or with 90 the ends of the segment, but the manner of applying the segment as shown, provides a smooth unbroken surface for engagement by the contact fingers, thus eliminating the destruction of the contact fingers through 95 engagement with the fastening means or with the ends of the segments.

We claim:

The combination with a control cylinder 100 having a single segmental contact member 105 projecting radially therefrom with its arcuate face concentric with said cylinder, a contact plate having an arcuate portion

seated solidly on said face and straight portions at each end in contact with said cylinder and with the radial faces of said member, and means for fastening said straight portions to said radial faces, said arcuate and straight portions being connected by semi-circular portions which project beyond

the straight portions and over said fastening means.

In testimony whereof we affix our signatures.

WILLIAM GARRETT.
GEORGE GAYLETS.
